(57) **CLAIM**

The ornamental design for a casserole, as shown and described.

DESCRIPTION

FIG. 1 is a top, front, and right side perspective view of a casserole according to the new design;

FIG. 2 is a top plan view thereof;

FIG. 3 is a front elevational view thereof, the rear view being a mirror image;

FIG. 4 is a left side elevational view thereof; the right side elevational view being a mirror image; and,

FIG. 5 is a bottom plan view thereof.

The broken lines shown in the drawings are for illustrative purposes only and form no part of the claimed design.
